(57) **CLAIM**

The ornamental design for the electronic device accessory case, as shown and described.

DESCRIPTION

FIG. 1 is a perspective view of an electronic device accessory case taken from the top, right, and front;

FIG. 2 is another perspective view of the electronic device accessory case taken from the top, left, and back;

FIG. 3 is a front elevation view of the electronic device accessory case of FIG. 1;

FIG. 4 back elevation view of the electronic device accessory case of FIG. 1;

FIG. 5 is a right elevation view of the electronic device accessory case of FIG. 1;

FIG. 6 is a left elevation view of the electronic device accessory case of FIG. 1;

FIG. 7 is a top plan view of the electronic device accessory case of FIG. 1; and,

FIG. 8 is a bottom plan view of the electronic device accessory case of FIG. 1.
